AUTOMATIC TELEPHONE SYSTEM

Filed Aug. 23, 1930

UNITED STATES PATENT OFFICE

JOHN WICKS, OF OAK PARK, ILLINOIS, ASSIGNOR TO RESERVE HOLDING COMPANY,
OF CHICAGO, ILLINOIS, A CORPORATION OF DELAWARE

AUTOMATIC TELEPHONE SYSTEM

Application filed August 23, 1930. Serial No. 477,214.

This invention relates to automatic telephone systems in general, particularly to automatic telephone systems which include satellite or branch exchanges and has for its object the provision of a new and efficient switching selector repeater for use in such systems.

Branch exchange trunking is ordinarily so arranged that a subscriber, on initiating a call, is connected with a selector repeater at the branch exchange, and a branch connection is simultaneously extended over a trunk line to an incoming selector in the main exchange. The selector repeater and the incoming selector operate in synchronism in response to the dialled impulses, and when sufficient digits have been dialled to determine the ultimate destination of the call, either the selector repeater is disabled for further operation or the branch connection is released. The switching operation takes place and is controlled by the selector repeater according to the number called.

Several methods of initiating the switching operation of the selector repeater are in common use. One method consists of wiring the selector repeater banks in a particular manner, so that the switching operation takes place when the switch wipers are positioned on certain sets of contacts. Another arrangement employs shaft springs which initiate the switching operation when the switch wipers are raised to a particular level. The first arrangement requires a complicated and relatively expensive bank wiring, while the second arrangement lacks flexibility, particularly when it is necessary to employ two or more digits for determining the routing of a call.

The above-referred to objectionable features are eliminated in the present invention, which employs a vertical wiper and a simple vertical contact bank individual to each selector repeater for controlling the switching operation. This arrangement permits the use of standard switch banks with the selector repeaters and constitutes one of the main features of the invention.

Another feature is the arrangement whereby no rotation of the switch wipers

takes place when a switching level is called. This permits the wipers to restore to normal position very rapidly after the first switching digit and prevents the wipers from occupying and tying up bank contacts after the final switching digit. The switch banks may, therefore, be used to their full capacity for local service in the branch exchange.

The foregoing features together with others not specifically mentioned will be described in more detail together with the operation of the equipment, reference being had to the accompanying single figure of drawing which discloses one embodiment of the invention.

Referring now to the drawing, there is shown an ordinary automatic substation T whose associated line terminates in the line-switch LS. Lineswitch LS may be of any well known type, for example, a rotary type lineswitch such as the one disclosed in applicant's co-pending application, Serial No. 395,882, filed September 28, 1929. Line-switch LS together with other similar line-switches has access to switching selector repeaters of which the selector repeater SR is shown. Selector repeater SR is the usual Strowger type switch having vertical and rotary movement, and in addition to the usual switch wipers is provided with a shaft wiper engaging a vertical contact bank individual to the switch. The selector repeater by way of its wipers has access to local connectors, such as the connector C. Connector C shown in skeleton form may be similar to the connector shown in the above referred to application. This connector has access to the branch-exchange subscribers' lines, such as the line extending to substation T1. Associated with the selector repeater is a lineswitch LS1 which has access to interoffice trunks connecting the main exchange and the branch exchange. One such trunk line is shown terminating in an incoming selector IS at the main exchange and an incoming selector IS1 at the branch exchange. The cut-off relay, line relay and release relay which are the only elements of the latter switch shown in detail

are similar to those of the incoming selector 100

shown in the previously referred to application. Both incoming selector IS and IS1 may be exactly the same as the incoming selector shown in the previously referred to application, and each has access to local switches in the respective exchanges. The trunk line is also accessible to the local switches in the main exchange for extending connections to branch exchange subscribers.

The system disclosed to illustrate the invention is a five digit system of which one one-thousand group of numbers is assigned for branch exchange lines. The numbers assigned to the branch exchange lines are in the same ten-thousand series as certain lines of the main exchange, which makes the switching selector repeater necessary. It is assumed for convenience that the numbers of the 34000 series are assigned to the branch exchange lines and that the remaining numbers beginning with the digit three, that is, numbers from 31000-33000 and 35000-39000 are assigned to main office lines. It is obvious, therefore, that any number excepting a 3 which constitutes the first digit designates a call as for the main exchange. Calls for numbers beginning with a three may be either for main exchange or branch exchange lines depending on the value of the second digit.

The subscriber at substation T on initiating a call is connected with an idle selector repeater, such as SR, by the lineswitch LS. Lineswitch LS1 operates responsive to the seizure of the associated selector repeater and extends a connection over an idle interoffice trunk line to an incoming selector, such as IS, at the main exchange. The subscriber then dials the five digits of the called number to complete the connection. In case the first digit dialled is any other than three, the selector repeater wipers are raised to the called level but do not rotate in, and the selector repeater is disabled from further operation. The incoming selector operates in synchronism with the selector repeater and selects an idle trunk extending to a local second selector in the main exchange. The second selector, third selector, and connector at the main exchange respond to the subsequent digits of the called number in the usual way to extend the connection to the wanted subscriber's line. In case the first digit of the called number is the digit three, the selector repeater and incoming selector operate in synchronism as before and the wipers of the selector repeater are restored to normal immediately after the completion of the first series of impulses. If the second digit of the called number designates a main exchange subscriber's line, the wipers of the selector repeater are raised to the called level but do not rotate and the selector repeater is disabled from further operation. The second selector at the main exchange

operates in synchronism with the selector repeater and selects an idle trunk in the called level. In the main office the third selector and connector respond to the final digits in the usual way to complete the connection. In case the second digit indicates a branch exchange subscriber's line in the above connection, the wipers of the selector repeater are restored to normal immediately after the digit is dialled. The automatic hunting circuit is prepared, and, responsive to the third digit of the called number, the selector repeater will select an idle trunk terminating in a branch exchange connector, such as the connector C. The branch connection to the main exchange will be released. The connector C will respond to subsequent digits and extend a connection to the subscriber's line in the usual way.

Calls to main exchange subscribers

In order to more clearly illustrate the utility of the invention, the operations involved in setting up various connections in a system embodying the invention will now be described in detail. It will be assumed first that a branch exchange subscriber, such as the subscriber at substation T, is calling the main exchange subscriber (not shown) whose number is 51101. When the receiver is lifted at substation T a loop circuit is closed for operating lineswitch LS in the usual manner, and the lineswitch selects a trunk terminating in a selector repeater, for example, the trunk comprising conductors 108-111 terminating in selector repeater SR. Impulse relay 3 of the selector repeater operates over the calling loop, the circuit extending from battery, upper winding of relay 2, right-hand winding of relay 3, normally closed contacts 22, conductor 108, wiper 104 of the lineswitch, line conductor 102, through the loop at the calling substation, line conductor 101, wiper 107 of the lineswitch, trunk conductor 111, normally closed contacts 29, left-hand winding of relay 3, lower winding of relay 2, to ground. Relay 2 is differentially wound and does not operate at this time. Relay 3 on operating prepares a control loop at contacts 32. Relay 3 also closes a circuit extending from ground, contacts 34, winding of relay 4, contacts 43, 66, and 92, winding of vertical magnet 15, to battery, and in parallel therewith, through the two windings of relay 8, to battery. Relay 4 operates over the above circuit, but due to its relatively high resistance, relay 8 and the vertical magnet do not operate at this time. Relay 4 on operating completes the testing circuit for lineswitch LS1 at contacts 36, connects the holding ground to release trunk conductor 110 at contacts 37, connects ground to the local holding circuit at contacts 38, prepares the impulsive circuit and a shunt circuit for it-

- self at contacts 39, opens the release circuit at contacts 41, and prepares a circuit for the vertical wiper at contacts 40. Ground on the local holding circuit extends by way of 5 normally closed contacts 71, winding of relay 13, interrupter contacts of stepping magnet 95, through the winding magnet 95, to battery. Relay 13 will operate over this circuit unless the wipers of the lineswitch 10 are standing on the contacts of a trunk which is in use, in which case ground from the upper armature and front contact of the release relay of the incoming selector over a conductor similar to conductor 15, 130 and the test wiper of the lineswitch will be extended by way of conductor 127, contacts 83, 67 and 36, to the lower terminal of relay 13, thereby shunting the relay and energizing stepping magnet 95. The stepping magnet energizes and 20 interrupts its own circuit, advancing the wipers to the next set of contacts where the testing operation is again performed. When an idle trunk is encountered for example the 25 trunk comprising conductors 135 and 136, the test wiper of the lineswitch will find no ground and relay 13 will operate in series with magnet 95, the magnet not operating, however, due to the relatively high resistance of relay 13. Relay 13 extends the control loop of the selector repeater to the lineswitch by closing contacts 81 and 85 and connects the test wiper of the lineswitch directly to the local holding circuit of the 30 selector repeater at contacts 84. Ground on this circuit operates cut-off relay 96 of the incoming connector which disconnects the line relay 97 from the incoming trunk, and extends the trunk conductors through to the 35 line wipers of the lineswitch. It will be understood that incoming selector IS at the main exchange is provided with a bridged line relay similar to relay 97, which now operates over the control loop. The control 40 loop incidentally extends from battery through the upper winding of differential relay 2, winding of relay 5, impulse contacts 32, normally closed contacts 24 and 87, contacts 81, conductor 125, upper wiper of lineswitch LS1, conductor 128, contacts 132, trunk conductor 135, through the winding of the impulse relay of incoming selector IS of the main exchange, lower trunk conductor 136, contacts 133, conductor 129, 55 lower wiper of lineswitch LS1, conductor 129, contacts 85 and 28, winding of relay 6, lower winding of relay 2, to ground. Relays 5 and 6 operate in series with the line relay of the incoming selector. Relay 9 in the 60 meantime is operated over a circuit from ground on the local holding circuit, contacts 63 and 69, lower winding of relay 9, to battery. The operation of relay 5 completes a locking circuit including the upper winding of relay 9, and contacts 62 and 45 to prevent the release of this relay during the setting up of the connection. The foregoing operations take place responsive to the initiation of a call and the apparatus is now in condition to receive the 70 dialled impulses. The calling subscriber now dials the first digit of the called number, that is, the digit 5, and interrupts the circuit of line relay 3 which responds in the usual manner. Each time relay 3 retracts its armature, release relay 4 is shunted at contacts 35, thereby permitting relay 8 and vertical magnet 15 to energize. Relay 8 is slow-to-release and maintains a shunt circuit around relay 6 by connecting ground directly to the control loop at contacts 56 to improve pulsing. Magnet 15 raises the wipers of the switch to the called level. The previously traced control loop which 75 extends to the main exchange is also interrupted at contacts 32 of the line relay and the impulse relay of the incoming selector responds accordingly. The wipers of the incoming selector are, therefore, raised to the fifth level where the automatic hunting 80 operation takes place in the usual manner. Shortly after the last impulse of the series relay 8 of the selector repeater deenergizes and completes a circuit from ground, contacts 40 and 55, vertical wiper 141, fifth 85 contact of the vertical bank which it will be noted is multiplied with the remaining contacts with the exception of the third and fourth contacts of the bank, contacts 73, winding of relay 10, to battery. Relay 10, 90 operates, and at contact 64 completes a locking circuit for itself to ground on the local holding circuit of the selector repeater. Relay 4 is now maintained energized in series with the lower winding of relay 8, 95 whose high resistance upper winding is short-circuited by the closure of contacts 65. No rotation of the switch wipers of the selector repeater take place under these conditions since the circuit of rotary magnet 16 100 is open at contacts 68, and consequently the wipers remain positioned opposite the fifth level of the banks. The calling subscriber now dials the second digit of the called number, assumed 105 to be digit 1, and relay 3 responds as in the previous instance. Relay 8 again responds but has no useful function at this time aside from shunting relay 6. The control loop 110 extending over the trunk line is interrupted at contacts 32 as in the previous instance and the second selector at the main exchange operates accordingly to select an idle third selector accessible in its first level. The operations responsive to the subsequent digits 115 of the called number are similar to those just described and serve to operate the third selector and connector at the main exchange. In case the called line is busy, the connector 120 will return the usual busy tone to inform the 125 130

calling subscriber of this fact. In the event that the called line is idle, the connector will seize the line in the usual way and the line relay at the connector will be disconnected from the control loop, thereby opening the circuits of relays 5 and 6 which release. Relay 5 opens the circuit of relay 9 at contacts 45, and relay 9 releases. Relay 9 switches the control circuit over to talking condition. When the called subscriber answers, talking battery is fed over the control loop through relays 5 and 6 and these relays operate over the called subscriber's loop. A circuit is now closed over contacts 45, 51 and 47 for relay 7 which operates and locks via contacts 61 to ground on the local holding circuit. Relay 7 prepares the metering circuit at contacts 49 and 50. The meter (not shown) on the calling line energizes but does not register until it deenergizes.

If the system is not arranged for zone metering no further operations take place while the conversation is in progress. When the called subscriber hangs up at the termination of the call, relays 5 and 6 will release. Relay 3 releases when the calling subscriber hangs up and opens the circuit of relay 4. Relay 4 closes a circuit for release magnet 17 including off-normal contacts 18 which closed on the first vertical step of the wipers. The release magnet operates and restores the switch wipers to normal in the usual way. Relay 8 operates from ground at contacts 42 during the releasing of the switch and maintains a busying ground in the release trunk at contacts 54 to prevent seizure of the switch. The control loop extending to the main exchange is opened at contacts 32 on the release of relay 3 and incoming selector IS and other switches in the main exchange restore to normal in the usual way.

In case the system is arranged for elapsed time metering, the main exchange will be provided with timing apparatus of the general type shown in the co-pending application of Wicks and Gould, Serial No. 432,688, filed March 3, 1930. At intervals during the course of the call, this apparatus will connect battery potential to the trunk line thereby shunting relay 5 of the selector repeater. Relay 5 on restoring will apply ground via contacts 44, 46 and 50 to the metering conductor, shunting the meter of the calling line which will restore and register a unit charge.

The subscriber at substation T to call subscriber No. 38101, for example, at the main office, will proceed as in the previous connection. The selector repeater and incoming selector will operate in synchronism in response to the first digit and vertical wiper 141 will come to rest on the third contact of the vertical bank. Shortly after the last impulse of the series relay 8 restores as before and completes a circuit via contacts 40 and 55, wiper 141, normally closed contacts 78,

lower winding of two-step relay 12, to battery. Relay 12 is adjusted so that when energized over its lower winding alone contacts 75 and 79 are closed but the remaining contacts remain in normal position. A circuit for operating the relay in its second step is prepared at contacts 75 which becomes effective on the opening of the initial operating circuit. Ground over the vertical wiper is also extended by way of contacts 79 which close and contacts 80 which remain closed as is normally the case, winding of release magnet 17, to battery. The release magnet operates and restores the switch wipers to normal position in the usual way. The release magnet on operating completes a circuit at contacts 42 for operating relay 8, and relay 8 in turn disconnects ground from the vertical wiper to open the initial energizing circuit of relay 12. Relay 12, therefore, operates in its second step, connects up relay 11, and disconnects itself from the vertical bank contact. The impulses are repeated over the control loop to the incoming selector at the main exchange as in the previous case and this switch operates to select an idle trunk to a second selector accessible in its third level.

The subscriber now dials the second digit of the called number in this case the digit 8, and a circuit is closed for relay 10 exactly as in the previous instance. Relay 10 operates and disables the selector repeater for further operation, thereby permitting the final digits to operate the third selector and connector at the main exchange as in the previous connection.

It will be noted that the fourth contact of the vertical bank is multiplied with all of the remaining contacts of the bank with the exception of the third contact, through normally closed contacts of relay 12. This is to permit the assignment of the fourth level for main exchange numbers and at the same time reserving this level for the critical second digit of branch exchange numbers.

Calls to branch exchange subscribers

The subscriber at substation T to call a subscriber at substation T1 which is also a branch exchange telephone line, will dial the five digits of the wanted subscriber which in this case will be assumed to be No. 34101. The selector repeater and lineswitch LS1 operate responsive to the initiation of a call as described for previous connections. The selector repeater and incoming selector at the main exchange are stepped to the third level responsive to the initiation of a call as described for previous connections. The selector repeater and incoming selector at the main exchange are stepped to the third level responsive to the first digit dialled, that is, the digit 3, and shortly after the last impulse of the series two-step relay 12 is energized

as in the call just described. The selector repeater SR and the second selector at the main exchange are operated to the fourth level in response to the second digit dialled, and, shortly after the last impulse of this series, relay 8 will again complete a circuit for applying ground to vertical wiper 141 which over contacts 76 will operate two-step relay 11 in its first step. Relay 11 is so adjusted that, when operated over its lower winding alone, contacts 70 and 72 will be closed while the remaining contacts will remain in their normal position. Relay 11 on operating in its first step will extend the ground from the vertical wiper by way of contacts 72 and 74, through the winding of release magnet 17, to battery. The release magnet operates and restores the switch wipers to normal in the usual manner and also close a circuit for operating relay 8. Relay 8 in turn disconnects ground from the vertical wiper which permits relay 11 to operate in its second step over two windings in series via contacts 70 to ground on the local holding circuit. Relay 11 on operating in its second step opens a point in the test circuit for lineswitch LS1 at contacts 67, opens the original energizing circuit of relay 9 at contacts 69, prepares a circuit for rotary magnet 16 at contacts 68, opens the circuit of relay 13 at contacts 71, opens the circuit of relay 10 at contacts 73, and opens the circuit of the release magnet at contacts 74. Relay 13 releases following the opening of its circuit, thereby disconnecting the control loop from the line wipers of lineswitch LS1. Although the control loop is opened at this time relay 5 will remain energized over a circuit extending over contacts 32, 24, 87 and 82, resistance 143, to ground on the local holding circuit. Resistance 143 is for the purpose of preventing the unbalance of relay 2 which would release the switch. The selector repeater will respond in the usual way to the third digit of the called number raising its wipers to the level called, in this case, the first level. Shortly after the last impulse of the series relay 8 will restore as in the previous case and a circuit is completed from ground at contacts 37, contacts 53, off-normal contacts 19 which closed on the first vertical step of the wipers, contacts 68, 90 and 94, winding of rotary magnet 16, to battery. The rotary magnet energizes, opens its own circuit at contacts 94, and steps the switch wipers to the first set of contacts in the bank. In the event that this set of contacts is busy wiper 113 will encounter ground or the absence of potential neither of which effect relay 14. The rotary magnet will consequently reoperate and advance the wipers another step and repeat the test for the succeeding trunk. These operations will be repeated until wiper 113 finds a contact marked idle by the presence of battery potential, at which time relay 14 will operate and open the circuit of the rotary magnet at contacts 90. Relay 14 locks in series with the rotary magnet over its lower winding via contacts 89 to ground 70 on the local holding circuit. The control loop will now be extended via contacts 86 and 93, wipers 112 and 114, trunk conductors 115 and 118, to the impulse relay of connector C. The impulse relay of connector C 75 will operate in series with relays 5 and 6 of the selector repeater. Relay 14 will also short-circuit its upper winding at contacts 88 to place a marking ground on the seized trunk line, and will disconnect magnet 15 80 from in series with relay 4 and short-circuit the high resistance upper winding of relay 8 to provide sufficient current to maintain relay 4 operated.

Relay 3 will respond to the next digit of 85 the called number and as before will interrupt the control loop at contacts 32 which loop, as previously stated, has been extended to the impulse relay of connector C. The impulse relay of the connector responds in 89 the usual way and the wipers of the switch are raised to the called level. The final digit of the called number is repeated through the selector repeater in the same manner and the wipers of the connector are 95 advanced to the contacts of the called line.

If the called line is busy the connector will return a busy tone to the calling subscriber to indicate this condition. In case the called line is idle, the connector will seize the line 100 in the usual way and the impulse relay of the connector will be disconnected from the control loop. Relays 5 and 6 of the selector repeater will restore as described in the previous connections, relay 5 opening the circuit 105 of relay 9 which restores and switches over the selector repeater to talking position. When the called subscriber answers relays 5 and 6 will operate since they are in the battery feed circuit and the metering circuit 110 will be prepared by the operation of relay 7 as previously described. Relays 5 and 6 will, of course, restore when the called subscriber hangs up, and when the calling subscriber restores his receiver relays 3 and 4 115 will restore and the selector repeater will release in the usual way. It may be noted that relay 8 operates following the restoration of relay 3 and due to its slow-to-release characteristic remains operated a short time 120 after the release of relay 4. Relay 8 maintains a ground on the release trunk to prevent the release of the calling subscriber's lineswitch until after the metering operation has taken place, and to mark the selector repeater busy during this release operation. This is for the purpose of preventing a calling line from seizing the selector repeater before the same has returned to normal.

What is claimed is:

1. A two-coordinate switching selector repeater for use in branch exchanges, said selector repeater comprising means for switching a call originating in the branch exchange 5 in which it is being used from the main exchange to said branch exchange when sufficient digits have been called to determine the destination of the call, and comprising a wiper positioned solely by the first coordinate movement of the selector repeater for controlling said switching means.

2. In a switching selector repeater for use in branch exchanges, said selector repeater adapted when seized by a calling branch exchange subscriber to extend a connection to the main exchange, wipers positioned by a vertical and rotary movement of the selector repeater for extending a call via a local trunk line in the branch exchange, 15 switching means for releasing the main exchange connection and for rendering the selector repeater effective to extend a connection via said wipers when sufficient digits have been called to identify the call as local, 20 and a wiper positioned solely by the vertical movement of the selector repeater for controlling said switching means.

3. In a switching selector repeater having a set of wipers adapted to be positioned by 30 two coordinate movements to extend a connection to a local trunk line, a control circuit initially extended over an outgoing trunk line responsive to the seizure of the selector repeater, and an auxiliary wiper 35 adapted to be positioned by the first coordinate movement of the selector repeater for controlling the switch-over of said circuit from the outgoing trunk to said set of wipers.

4. In a switching selector repeater for use in a branch exchange, said selector repeater being adapted to repeat the initial digits of a called number over a trunk line to operate a series of automatic switches in the 45 main exchange, switching means for releasing the main exchange connection and for adapting the selector repeater to extend a connection over a local trunk line via a set of wipers positioned by a vertical and rotary stepping movement, and an auxiliary wiper positioned solely by the vertical stepping movement of the selector repeater for controlling said switching means.

5. In a telephone system, main and branch exchanges and interconnecting trunk lines, automatic switches in the main exchange, a switching selector repeater accessible to calling branch exchange subscribers adapted to repeat impulses over an inter-office trunk 60 line to operate a series of main exchange switches, means for simultaneously operating the selector repeater in its primary movement and the first of the series of main exchange switches responsive to the first 65 digit of the called number, means for pre-

venting further directive operation of the selector repeater when such digit indicates a call for a main exchange subscriber, and a wiper positioned only by the primary movement of the selector repeater for controlling said last means. 70

6. In a switching selector repeater having a set of line wipers positioned by a vertical and rotary stepping movement and an auxiliary wiper positioned solely by said vertical stepping movement, switching means for determining whether a connection is to be extended over said line wipers or independent thereof, and contacts engaged by said auxiliary wiper for controlling said 75 switching means.

7. In a telephone system, main and branch exchanges and interconnecting trunk lines, automatic switches in the main exchange, a switching selector repeater accessible to calling branch exchange subscribers adapted to repeat impulses over an inter-office trunk line to operate a series of main exchange switches, means for simultaneously operating the selector repeater in its primary movement and the first of the series of main exchange switches responsive to the first 85 digit of the called number, means for restoring the selector repeater to normal when such digit indicates a call for a subscriber's line which may terminate in either exchange, and a wiper positioned only by the primary movement of the selector repeater for controlling said last means. 90

8. In a telephone system, main and branch exchanges and interconnecting trunk lines, automatic switches in the main exchange, a switching selector repeater accessible to a calling branch exchange subscriber adapted to repeat impulses over an inter-office trunk line to operate a series of main exchange switches, means for simultaneously operating the selector repeater in its primary movement and the first of the series of switches at the main exchange responsive to the first digit of the called number, means for releasing the selector repeater when such digit designates a line which may be in either exchange, means for simultaneously operating the selector repeater in its primary movement and the second of the series of switches at the main exchange responsive to the second digit of the called number, means for disabling the selector repeater from further operation when said second digit designates a main exchange subscriber's line, and a wiper positioned by the primary movement of the selector repeater for controlling said releasing and disabling means. 100

9. In a telephone system, main and branch exchanges and interconnecting trunk lines, automatic switches in the main exchange, a switching selector repeater accessible to a calling branch exchange subscriber 105

adapted to repeat impulses over an inter-office trunk line to operate a series of main exchange switches, local trunk lines accessible to the selector repeater, means for simultaneously operating the selector repeater in its primary movement and the first of the series of main exchange switches responsive to the first digit of the called number, means for releasing the selector repeater when said

10 first digit designates a line which may be in either exchange, means for simultaneously operating the selector repeater in its primary movement and the second of the series of main exchange switches responsive to the second digit of the called number, means for releasing both the selector repeater and the main exchange switches when said second digit designates a branch exchange line and for preparing the selector repeater to connect with one of said local trunk lines, and a wiper positioned by the primary movement of the selector repeater for controlling said releasing and preparing means.

15 10. In a switching device having a set of wipers adapted to be positioned responsive to a primary stepping movement and a secondary stepping movement, an auxiliary wiper adapted to be positioned by said primary stepping movement alone, and means controlled by said auxiliary wiper for preparing the device to operate in its secondary stepping movement.

20 11. In a switching device having directive primary movement and automatic secondary movement, a set of wipers positioned by said two movements, and an auxiliary wiper positioned by said primary movement alone for determining whether or not said secondary movement shall take place.

25 12. In a switching device having directive primary movement and automatic secondary movement, a set of wipers positioned by said two movements, an auxiliary wiper positioned by the primary movement alone, means normally effective to prevent the secondary movement of the device, and means controlled by said auxiliary wiper for disabling said last means.

30 13. In a switching device having directive primary movement and automatic secondary movement, a set of wipers positioned by said two movements, an auxiliary wiper positioned by the primary movement alone, means normally effective to prevent the secondary movement of the device, and means controlled by said auxiliary wiper when positioned in a particular manner for restoring the wipers to normal position and for disabling said last means.

35 14. In a switching device having directive primary movement and automatic secondary movement, a set of wipers positioned by said two movements, an auxiliary wiper positioned by the primary movement alone, means normally effective to prevent the sec-

ondary movement of the device, means controlled by said auxiliary wiper when operated to one position for restoring the switch wipers to normal, and means controlled by said auxiliary wiper when re-operated to another position for restoring the switch wipers to normal and for disabling said secondary movement preventing means.

40 15. In a switching selector repeater adapted to be directly operated in its vertical movement and to rotate in search of an idle local trunk line when used in a local connection, means for directly operating the selector repeater in its vertical movement and for preventing the rotary movement when used in an inter-office connection, and means for maintaining the selector repeater in its vertically operated position until the inter-office connection is released.

45 16. In a switching selector repeater, vertical and rotary stepping magnets, means for operating the vertical magnet when the selector repeater is used in either local or outgoing calls, and means for operating the rotary magnet only when sufficient digits have been called to designate the call as a local one.

50 17. In a switching selector repeater, vertical and rotary stepping magnets, means for operating the vertical magnet responsive to both first and second digits of called numbers in either local or outgoing calls, and means for operating the rotary magnet only when the second of said digits designates the call as a local one.

55 18. In a switching selector repeater, line wipers, means for raising said wipers step-by-step to a called level in both local and outgoing calls, means for rotating said wipers only in local calls, and a vertically moving auxiliary wiper for controlling said last means.

60 19. In a telephone system, main and branch exchanges and interconnecting trunk lines, a switching selector repeater adapted to respond to one or more digits of a called number simultaneously with switches in the main exchange, a control circuit including a source of current in the branch exchange for controlling said main exchange switches, and means in the selector repeater for releasing the connection to the main exchange and for extending said control circuit to a local switch in the branch exchange when sufficient digits have been called to designate the call as a local one.

65 20. In a telephone system comprising main and branch exchanges interconnected by trunk lines, a switching selector repeater in the branch exchange adapted to extend a control circuit to the main exchange, said circuit including a source of current in the branch exchange and one of said trunk lines, means for interrupting said circuit

to operate a series of automatic switches in the main exchange, and means in the selector repeater for switching over said control circuit from the trunk line extending to the main exchange to a trunk line extending to a local switch in the branch exchange.

21. In a telephone system, a main exchange and a branch exchange, a switching selector repeater in the branch exchange, means for extending a connection from the branch exchange to the main exchange responsive to the seizure of the selector repeater by a branch exchange subscriber, a pair of impulse contacts in the selector repeater included in said connection for controlling switching apparatus at the main exchange, wipers for the selector repeater positioned by a vertical and rotary movement for extending a connection over a local trunk in the branch exchange, switching means in the selector repeater operative to release the main exchange connection and to transfer said impulse contacts to the local connection for controlling switching apparatus in the branch exchange, and an auxiliary wiper for the selector repeater positioned solely by the vertical movement thereof for operating said switching means.

22. In a telephone system, a main exchange and a branch exchange, a switching selector repeater in the branch exchange, means for extending a connection from the branch exchange to the main exchange responsive to the seizure of the selector repeater by a branch exchange subscriber, a battery feed bridge in the selector repeater included in said connection for supplying talking current to a called subscriber, wipers for the selector repeater positioned by a vertical and rotary movement for extending a connection over a local trunk in the branch exchange, switching means in the selector repeater operative to release the main exchange connection and to transfer said battery feed bridge to the local connection, and an auxiliary wiper for the selector repeater positioned solely by the vertical movement thereof for operating said switching means.

23. In a switching selector repeater having a set of wipers adapted to be positioned by two coordinate movements to extend a connection to a local trunk line, a set of impulse contacts, a control circuit including said contacts extended over an outgoing trunk line responsive to the seizure of said selector repeater, switching means for transferring said impulse contacts from said first control circuit to a second control circuit including said set of wipers, and an auxiliary wiper positioned by the first coordinate movement of said set of wipers for controlling said switching means.

24. In a telephone system comprising main and branch exchanges interconnected

by trunk lines, a switching selector repeater in the branch exchange adapted to initially extend a connection over one of said trunk lines to switching apparatus in the main exchange, a set of impulse contacts in the selector repeater for controlling the main exchange switching apparatus over said connection, means for releasing said connection and for extending another connection to switching apparatus in the branch exchange, and means including said set of contacts for controlling the branch exchange switching apparatus over said other connection.

25. In a telephone system comprising main and branch exchanges interconnected by trunk lines, a switching selector repeater in the branch exchange, means for simultaneously operating the selector repeater and switching apparatus in the main exchange during the establishment of a connection to a called subscriber in either exchange, means for disabling the selector repeater for further operation or for releasing the main exchange switching apparatus when the establishment of the connection has progressed far enough to determine in which exchange the called subscriber is located, and means in the selector repeater for feeding talking battery to a called subscriber located in either exchange.

In witness whereof, I hereunto subscribe my name this 19th day of August, A. D. 1930.

JOHN WICKS.
